UNITED STATES PATENT OFFICE

BYRON C. GOSS, OF CLEVELAND, OHIO

BANK VAULT VENTILATOR SYSTEM

Application filed May 15, 1930. Serial No. 452,714.

This invention relates to improvements in bank vault ventilator systems, such as are used in banks, and similar chambers in which people are apt to be accidentally confined, to ventilate the atmosphere in such vault or chamber, by pumping or otherwise delivering fresh air into the vault or chamber through an air circuit.

An object of the present invention is to maintain control over the purity of the air which the ventilator system pumps into the vault or chamber by placing in the path of the stream of air a suitable "tear gas" absorber, or filter, such as are used in gas masks, containing a quantity of an absorbing composition which will absorb, or filter, from the in-flowing stream of air any "tear gas" or similar irritating asphyxiating, or disabling gas which may have been dispersed through the atmosphere outside of the wall, and which atmosphere is pumped into the vault or chamber through the air circuit.

A further object is to provide a portable ventilator with a gas filter, that may be inserted in cone-shaped ventilating tubes that have been installed in bank vaults.

On many occasions, bank bandits have locked employees and others in the bank vaults in order to prevent or delay the sounding of an alarm, and thereby facilitate the escape of the bandits without risk of immediate capture. If the persons confined in the vault are not released within a reasonable time, suffocation, and sometimes death results from their confinement. In order to save the lives of any persons who may be accidentally confined in a vault, many banks have installed "vault ventilating systems" in their bank vaults. These ventilating systems are operated when desired from within the vault, and are under the control of the persons within the vault at all times, enabling them to pump fresh air into the vault at will. The air circuit passes through the wall of the vault, but because of local conditions, it is customary to have the intake of the air supply of the ventilator system open into the bank room, partly because the distance from the wall of the vault to the outside of the building is quite long, and partly

to prevent outside persons interfering with the air supply; accordingly, bank room atmosphere is ordinarily pumped into the vault. During attacks upon banks by bandits, it frequently happens that "tear gas" or a similar irritating gas is used by someone, either by the bank officials in the vault, or elsewhere, by bank bandits, or by police authorities, which contaminates the atmosphere in the bank room. If any people have been locked up in the vault, and "tear gas" or other irritating gas has been used, the vault ventilator will pump the bank room atmosphere which has been contaminated with the irritating gas into the vault, and the people within the vault will suffer greatly unless they are quickly released therefrom. The present invention provides a means to insure the safety of the confined person by absorbing or filtering the irritating gas from the stream of air which is being drawn into the vault through the air circuit. The absorbing or filtering material is contained in a suitable canister, and resembles in general the composition used in gas masks, and in the present invention the canister is suitably located so as to be quickly attached to the air circuit of the ventilator system, preferably by the persons confined in the vault; and may be readily detached from the air circuit when not needed. Or the canister may be permanently connected as described hereafter. The ventilator system is so arranged that when desired a continuous stream of fresh air may be delivered into the vault for ventilation purposes without the use of the canister, and the system may be used at any time to maintain a wholesome atmosphere within the vault. In practice, the canister is only connected in the air circuit when it is necessary to filter irritating gas from the atmosphere being pumped into the vault.

In the accompanying drawings,

Fig. 1 is a view of a preferred type of a ventilator system controlled from within the vault, with an air inlet pipe passing through the wall of the vault and connected to a suitable pump which discharges the indrawn air

through a suitable canister containing a "tear gas" filter;

Fig. 2 is a view of an air discharge pipe connected to a 3-way valve, so as to control 5 the delivery of the air;

Fig. 3 is a view of a modification of a ventilator system showing the canister containing the "tear gas" composition at the inlet end of the air circuit, behind a suitable 10 detachable shield;

Figs. 4 and 5 are views of a type of cone-shaped tube ventilator built into a vault wall with cone-shaped ventilators inserted therein;

Fig. 6 is a plan view of a cone-shaped canister to be placed in the cone-shaped ventilating tubes;

Fig. 7 is a section on the lines 7—7 of Fig. 5 showing the outer wall of the cone-shaped tube which is built into the wall, also the wall of the ventilating tube, and also of the cone-shaped canister therein, and also showing the filtering material; and

Fig. 8 is a view of a cone-shaped ventilator 23 without the canister, to be inserted in the cone-shaped tube in the vault wall.

In Fig. 1, the ventilating system or air circuit comprises a suitable motor driven pump, 1, which pumps air through the pipe 2 passing through the vault wall 3, the air being drawn in through the perforated plate 4 on the outside of the vault wall; the air stream passes through the pipe 2, through the pump actuated by motor 1, and is discharged through pipe 5 and canister 6, which latter contains an approved type of irritating gas or "tear gas" absorbing and filtering composition 29, Fig. 7. The canister 6 is arranged to be quickly attached to and detached from the pipe 5, and when not needed is detached.

As shown in Fig. 2, the air discharge pipe 5 may be connected to a 3-way valve 7, which will deliver the air either to the free outlet 8, or through the canister 9. This arrangement is advantageous for the reason that the irritating gas, or "tear gas" composition would have a longer life if not in constant use, while the provision of the 3-way valve makes it immediately available.

In Fig. 3, an approved type of irritating gas, or "tear gas" canister 10 is connected to the air pipe 11 at the inlet end; in Fig. 3, the air circuit comprises the pipe 11 in the vault wall 12, and terminates within a casing 13 behind a detachable perforated plate 14 on the outside of the vault, the canister 10 being attached to the end of the pipe, and the purified air discharged within the vault 60 through the free outlet 15.

In Fig. 4, a cone-shaped tube 18 is built into the vault wall 17, and ordinarily is empty. When desired, a cone-shaped ventilator 19, shown in Fig. 8, is placed in the tube 18. The ventilator 19 consists of a cone-

shaped tube 20, Fig. 8, which fits snugly in the tube 18, and is provided with a motor driven fan 21, shown in dotted lines, and actuated by the switch 22. A section 23 is cut out of the tube 20, to provide an opening through which is inserted a suitably shaped canister 24 shown in Fig. 6, and which latter is pressed to the small end of the tube 20. The ventilator containing the canister 24 is then inserted in the tube 18. The air is pumped through the canister as shown by the arrows, and filtered, and the purified air delivered into the vault.

In Fig. 5, a similar cone-shaped tube 18 is built into the wall 17, and when desired 80 there is inserted therein a cone-shaped ventilator 25 (see Fig. 8) resembling in general the cone tube 20. In the tube 25 is an opening 26, the edges of which are turned down as shown in dotted line at 27—27, to provide 85 narrow ridges or flanges on each side of the opening, and within the opening 26 and supported on each side by the flanges 27 is placed a canister 28 similar to canister 24 shown in Fig. 6, but having a larger diameter. The 90 cone-shaped ventilators 19 and 25 are conveniently located within the vault so as to be easily accessible for quick insertion in the cone-shaped tubes 18 should their use be necessary.

I claim:

In a vault ventilating system, an air circuit comprising an inlet, a positive air drive, and an outlet, a 3-way valve comprising an intake and two exhausts, the intake of said 100 valve connected to said outlet, one exhaust connected to an irritating gas filter and the other exhaust opening into the vault, which on turning said valve the gas filter may be disconnected from said air circuit.

In testimony whereof I, hereby affix my signature.

BYRON C. GOSS.
